Jerry Shapiro, 585 Lawn Terrace, Mamaroneck,
N.Y. 10543; and Philip Shapiro, 90 Riverside Drive,
New York, N.Y. 10023

Filed Dec. 19, 1966, Ser. No. 5,092

Term of patent 14 years

(Cl. D92—2)

The figure is a perspective view of a bedspread or similar article showing our new design as it appears when draped over a bed and pillow.

The portions of the instant invention not disclosed are similar to the portions shown.

We claim:

The ornamental design for a bedspread or similar article, as shown and described.
